UNITED STATES PATENT OFFICE.

WILLIAM H. MAGEE, OF MOUNDSVILLE, WEST VIRGINIA, ASSIGNOR TO FOSTORIA GLASS CO., OF MOUNDSVILLE, WEST VIRGINIA, A CORPORATION OF WEST VIRGINIA.

DISPLAY STAND.

Application filed March 30, 1926. Serial No. 98,572.

This invention relates to display stands such as used in store windows and the like, and has particular reference to the display of shoes, slippers, etc.

5 An object of the invention resides in the provision of such a stand or a head therefor which will be neat and attractive in appearance and which when in use will be disposed entirely within the outline of the article 10 being displayed thereby eliminating a tendency to distract the observer's attention from the article itself.

Another object of the invention consists in the production of a head for shoe stands 15 made in a single piece without moving parts, and yet which will allow the shoe to be exhibited at varying angles in a vertical plane so as to present the most advantageous display thereof.

20 Another object of the invention resides in the provision of a one-piece head for display stands which may be mounted on various types of bases, and in the construction of an adapter for use in providing a tight 25 fit between the parts irrespective of slight variations in their sizes.

Other objects and advantages of the invention will be apparent from the following description when taken in connection 30 with the accompanying drawings, in which:

Figure 1 is a side elevation of the improved display stand showing two positions of a shoe in dotted lines.

Figure 2 is a perspective view of the display head per se.

Figure 3 is a perspective view of the adapter; and

Figure 4 is a plan view of the head.

Referring to the drawings in greater detail the numeral 1 designates a base preferably formed of glass and in the present embodiment of the invention disclosed as a candlestick provided with a socket 2. It will be understood of course that other types 45 of bases may be used as desired, and if preferred may be made integral with the head to be described below.

The head of the display stand, which is also preferably made of glass, is a one-piece 50 structure indicated generally by the numeral 3 and provided on its lower end with a plug 4 adapted to be seated in the socket 2 of the base portion. The body of the head 3 has integrally formed thereon a pair of horizontally-spaced, forwardly extending pro-

jections 5 adapted to form a rest for the toe or forward part of the shoe being displayed, while extending rearwardly and upwardly therefrom is a stem 6 also integrally formed and provided with a down-turned end portion 7. This curved end portion 7 is formed with a plurality of spaced ledges 8, on any one of which may rest the heel of the shoe which is indicated by the numeral 9. Obviously, the series of ledges 8 permits the shoe 65 to be tilted to any preferred position for display without any adjustment of set screws or the like as has been necessary in shoe stands heretofore in use.

In the present embodiment of the invention, in which a separable base and head are employed with a plug and socket connection, it is desirable that an adapter be used to compensate for any inequalities in the sizes of the plug and socket. To this end I have 70 provided the member 10 preferably made of some resilient material such as rubber and formed with the spaced, longitudinal ribs 11. In applying the head 3 to the base 1, the adapter 10 may be applied to the plug 4 or to the socket 2 and the plug then inserted 80 into the socket. The adapter is, of course, closed at its lower end.

It will be understood that the invention herein disclosed particularly contemplates the use of the head with a separate base; the base being preferably in the form of a candlestick and the height may vary from the low or squat type of candlestick to tall candlesticks of any desired height. But the 85 invention also contemplates a structure in which the head is integrally formed with the base or pedestal; and further, the base or pedestal may be entirely omitted, and in place of the plug 4 the lower portion of the 90 head may be flared to a sufficient width to function as a support for the head, thereby 95 providing a very low display stand.

From the foregoing description taken in connection with the accompanying drawings it will be observed that I have devised an exceedingly simple display stand for shoes, which is not only neat and attractive in appearance, but also is capable of displaying shoes at the most advantageous angles 100 without the necessity of mechanical adjustments of any kind.

In accordance with the patent statutes I have described what I now believe to be the best embodiment of the invention, but I 110

do not wish to be understood thereby as limiting myself or the scope of the invention, as many changes and modifications may be made without departing from the spirit of the invention; all such I aim to include in the scope of the appended claims.

What I claim as new and desire to secure by Letters Patent is:

1. In a display stand for shoes, a non-tiltable head including a downwardly inclined rear end provided with means formed thereon for supporting the heel of a shoe in varying vertical positions.
2. In a display stand for shoes, a head including a downwardly curved rear end provided with a plurality of spaced ledges for supporting the heel of a shoe in varying positions.
3. In a display stand for shoes, a head including an upwardly inclined stem terminating in a downwardly curved end portion provided with means formed thereon for supporting the heel of a shoe in varying vertical positions.
4. In a display stand for shoes, a head including a forwardly extending projection

adapted to support the toe of a shoe, and a rearwardly and upwardly extending portion provided with a curved end, and means on said curved end for supporting the heel 30 of the shoe in varying vertical positions.

5. In a display stand for shoes, a head including a pair of horizontally-spaced forwardly extending projections adapted to support the toe of the shoe, and a rearwardly extending curved portion provided with means for supporting the heel of the shoe in varying vertical positions.

6. In a display stand for shoes, a one-piece head including a forward projection, an upwardly inclined stem, a downwardly curved rear end, and a plurality of ledges spaced along said curved end.

7. In a display stand for shoes, a substantially vertical stem, an integral forward portion adapted to support the toe of a shoe, an integral rearward portion adapted to support the heel of a shoe, and means formed integral with said rearward portion for positioning the heel at varying 50 heights.

WILLIAM H. MAGEE.
